UNITED STATES PATENT OFFICE

2,533,948

EDGE CLEANING APPARATUS

Jerome R. Marcus and Frederick W. Turner, Chicago, Ill., assignors to Western Electric Company, Incorporated, New York, N. Y., a corporation of New York

Application July 11, 1945, Serial No. 604,462

12 Claims. (Cl. 15—21)

1

This invention relates to an edge cleaning apparatus and more particularly to an apparatus for removing insulation from the wires wound on potentiometer insulators.

In the manufacture of high-precision potentiometers, fine insulated wire is wound on relatively thin strips of insulating material called "cards," the width of which may vary over a wide range, whereby the desired amount of conductor may be wound in a given length of the card. After these cards have wire wound on them, they may be assembled in potentiometers in position to have one edge of the winding engaged by a sliding contact. Since the circuit through the winding must be completed along one edge of the card, it becomes necessary to remove the insulation from the wire along that edge.

It is an object of the present invention to provide a simple and effective mechanism for rapidly 20 cleaning the edge of an article.

In accordance with one embodiment of the invention, a wound potentiometer card is clamped to a table by spring pressed clamping devices arranged along the length of the card and the table which receives the card. In order to accurately locate the card in position on the table, a gage is provided for aligning the edge of the card which is to be cleaned in position extending a predetermined distance beyond the edge of the 25 table which supports it in position to be engaged by a pair of wire brushes rotated in opposite directions and driven by suitable gearing from a common drive means. In the preferred form of the invention, the brushes are mounted on a carriage aligned to travel parallel to the edge of the card supporting table by a screw feed device, the brushes and their driving means being mounted together on the carriage in position to be individually adjusted horizontally and vertically with respect to the carriage.

A complete understanding of the invention may be had by reference to the following detailed description when considered in conjunction with the accompanying drawings, wherein

Fig. 1 is a plan view of an apparatus embodying the invention, part being broken away to conserve space, and showing the apparatus in inoperative position;

Fig. 2 is a wiring diagram of a control circuit for the carriage drive;

Fig. 3 is a rear elevational view showing the apparatus as viewed in the direction of the arrows along the line 3—3 of Fig. 1;

Fig. 4 is a fragmentary enlarged plan view of

5 a portion of the apparatus shown in Fig. 1 showing the apparatus in one of its operative positions where the brushes have started to clean the insulation from the wire at the edge of the potentiometer card;

Fig. 5 is a vertical sectional view taken substantially along the line 5—5 of Fig. 4 in the direction of the arrows;

Fig. 6 is a transverse vertical sectional view 10 on an enlarged scale taken along the line 6—6 of Fig. 1 in the direction of the arrows and showing one of the clamping mechanisms in its inoperative position;

Fig. 7 is a fragmentary view of the upper end 15 of one of the clamping devices shown in a partially operated position;

Fig. 8 is a view of one of the clamping mechanisms taken looking in the direction of the arrows along the line 8—8 of Fig. 6;

Fig. 9 is a transverse vertical sectional view 20 on an enlarged scale, taken substantially along the line 9—9 of Fig. 4, and showing one of the clamping members in its completely operated position; and

Fig. 10 is a sectional view taken through one 25 of the potentiometer cards and showing the manner in which the wire brushes engage an edge of the card for removing the insulation from the wire wound on the card.

30 In the drawings, a potentiometer card 15 of the type processed in this apparatus is most clearly illustrated in Figs. 4 and 10. The card 15 has one straight side or edge 16, whereas its rear edge 17 is of irregular contour whereby a desired amount of resistance wire 18 may be wound on the card to provide varying amounts of resistance for equal sections of the length of the card. The wire 18 is coated with insulation such, for example, as enamel, and is wound upon the card 15 in any suitable winding machine, whereupon the insulation must be removed from the wire 18 at the edge 16 for engagement by a sliding contact forming a part of the potentiometer. The apparatus of the present invention provides an effective 40 means for accomplishing the removal of such insulation.

The apparatus includes a base member 22 on which the various parts of the apparatus are mounted. This base member has a plate 23 suitably secured thereto and forming a part of a framework including end frames 24 and 25. Interposed between the end frames 24 and 25 is a channel member 26 having its lower flange mounted on the plate 23 and carrying a table 27 on its upper flange. The table 27 is adapted to

support a potentiometer card 15 during the cleaning of the forward edge 16 thereof. The end frames 24 and 25 extend upwardly beyond the table 27 and serve to support support plates 28 and 29. Secured to and extending between the support plates 28 and 29 is a channel member 30, on which a plurality of clamping assemblies, designated generally by the numeral 31, are suitably mounted. All of the clamping assemblies 31 are of exactly the same construction and only one of them will be described in detail.

In each clamping assembly there is provided a pair of push rods 32, having enlarged lower portions 33 and reduced upper shank portions 34. The lower portions 33 of the rod 32 are slideable in suitable apertures 35 formed in the lower flange of the channel member 30, whereas the reduced shank portions 34 of the push rods 32 are slideable in apertures 36 in the upper flange of the channel member 30. At their lower ends, the push rods 32 are fixed to a clamping plate 37 having a suitable clamping pad 38 of resilient material, such as felt attached thereto. Seated on the shoulders formed at the juncture of the upper and lower portions of the push rods 32 are washers 39, against which compression springs 40 bear. The compression springs 40 are interposed between the washers 39 and a cross plate 41, which is slideable with respect to the push rods 32, and is interposed between the springs 40 and collars 42 suitably pinned to the push rods. Intermediate the push rods the cross plate 41 has a pivot bearing 43 mounted thereon, in which a lever 44 is pivotally mounted. The lever 44 is pivotally interconnected with an actuating lever 45 by a link 46 and is interconnected with a stationary plate 47 by a pair of links 48. The stationary plate 47 is, in turn, mounted upon a bracket 49 fixed to the channel member 30. The stationary plate 47 is cut out to provide stops so that lever 45 can be positioned slightly below horizontal (Fig. 9) and slightly beyond vertical (Fig. 6), whereby the linkage will remain in either of its extreme positions.

These clamping assemblies 31 may be individually and manually operated to clamp potentiometer cards 15 on the table 27 under the pressure of the springs 40 under compression, the movement of the actuating lever 45 from the position shown in Fig. 6 through the position shown in Fig. 7 to the position shown in Fig. 9, serving to move the push rods 32 downwardly to carry the clamping pads 38 into engagement with the potentiometer card 15 on the table 27. It will be apparent, from a consideration of Figs. 6 to 9, inclusive, that, in either of its extreme positions, the clamping lever 45 will tend to remain in that position until moved manually therefrom.

In positioning a potentiometer card 15 on the table 27 to have the edge of it cleaned in the apparatus, a gage member 60 is used to position the card for engagement by a pair of brushes 61 and 62. The gage member 60 comprises an angle bar mounted upon the ends of a pair of levers 63 and 64 fixed to a shaft 65, which is journaled in journal blocks 66 fixed to the channel member 26 at spaced intervals along its length. The levers 63 and 64 have weights 67 and 68 at their free ends for counterbalancing the weight of the gage member 60 and the gage member may be held in either the position shown in Fig. 6 or the position shown in Fig. 9 by a pair of off-center spring assemblies 69. Each of the off-center spring assemblies 69 (Fig. 9) comprises a block 70 pivotally mounted on an end of a post 71

and carrying a rod 72. The posts 71 are fixed to the levers 63 and 64 and the rod 72 extends through blocks 73 pivotally mounted on the end frames 24 and 25. A spring 74 is interposed between the blocks 70 and 73, whereby, when the levers 63 and 64 are moved from the position shown in Fig. 6 to the position shown in Fig. 9 or vice versa, the springs 74 will tend to hold the gage member 60 in either of these positions due to the engagement of the edge of the gage member with the web of the channel member 26 or the engagement of the lever 63 with a stop member 77 on the upper flange of the channel member 26.

In the operation of the apparatus, the gage member 60 may be moved to the position shown in Fig. 6 and a wound potentiometer card 15 may be placed in engagement with it and clamped in place by the clamping assemblies 31, whereupon the levers 63 and 64 may be rocked to the position indicated in Fig. 9 to move the gage member out of the path of the brushes 61 and 62. When the gage member 60 is in the position shown in Fig. 6, the weight 67 will open a switch 75 suitably mounted from the base 22 in position to carry its actuating button 76 in the path of movement of the weight 67, as will be explained more in detail in connection with the description of the operation of the apparatus.

Mounted on the base member 22 (Figs. 6 and 9) is a block 80 having a guide tongue 81 extending longitudinally of it for engaging the side walls of a guide slot 82 formed in a carriage 83. The carriage 83 is provided with wheels 84—84, which ride on the upper surface of the block 80 and serve to support the carriage 83 for movement longitudinally of the base member 22 parallel to the edge of the table 27. The block 80 has bearings 85 extending therefrom for rotatably supporting a feed screw 86, which is threaded into a travelling nut 87 extending from the carriage 83. The feed screw 86 is adapted to be driven by a motor and speed reducer unit 88 through a conventional gear train enclosed in a housing 89.

Mounted on the carriage 83 is a motor 90 having a driven shaft 91 carrying a drive gear 92, which meshes with a pinion 93 on a shaft 94. The shaft 94 is journaled in bearings 95 and 96 and carries intermediate the bearings a split, adjustable pulley 97 of conventional design, which may be adjusted to vary its effective diameter with respect to a belt 99 engaging it. A pulley 98 of the same construction as pulley 97 is mounted to be driven by the belt 99 and, by differential adjustment of the two pulleys, their effective diameter may be adjusted to change the speed of driven pulley 98. The bearings 95 and 96 are mounted upon a plate 100, which is provided with a pair of slots 101 and 102 for receiving shouldered studs 103 and 104, the shanks of which are encircled by springs 105 and 106. The springs 105 and 106 are interposed between the heads of the studs and the upper surface of the plate 100 to resiliently clamp the plate 100 on the carriage 83. The plate 100 may be slid transversely of the carriage 83 by means of a locating screw 107 threaded into a bracket 108 on the plate 100 and rotatably supported in a bracket 109 on the carriage 83. The locating screw 107 is provided with graduations, as indicated at 110, for indicating the relative position of the plate 100 with respect to the carriage 83.

The pulley 98, with which the belt 99 is engaged, is mounted upon a shaft 111 journaled

in bearings 112 and 113 and carrying the wire brush 61. The bearings 112 and 113 are secured to a support plate 115, which may be mounted in spaced relation to the plate 100 by interposing spacer plates 116 between the upper surface of the plate 100 and the support plate 115, thus to regulate the height of the wire brush 61 for a purpose which will become apparent as the description progresses.

The shaft 94, as shown most clearly in Fig. 3, has a gear 125 mounted on its right end for engagement with a gear 126 on a shaft 127. The shaft 127 is journaled in bearings 128 and 129 and carries intermediate the bearings a pulley 130, similar to the pulley 97. The bearings 128 and 129 are mounted on a plate 131, similar to the plate 100, and the plate 131 may be adjusted with respect to the carriage 83 by means of an adjustment screw assembly 132 of exactly the same construction as the assembly provided for adjusting the plate 100 with respect to the carriage. Similarly, a belt 133, corresponding to the belt 99, drives a pulley 134 on a shaft 135. The shaft 135, like the shaft 111, carries the wire brush 62 and is mounted in bearings 137 and 138 fixed to a support plate 139. It will be noted, by reference to Fig. 5, that the support plate 139 is spaced from the plate 131 by a slightly greater amount than the support plate 115 is spaced from its plate 100 by a spacer plate 140, which is slightly thicker than the spacer plate 116. Thus the wire brush 62, which rotates in the direction indicated by the arrow (Figs. 4 and 10) being slightly higher than the brush 61, will engage the upper edge of the wire 18 wound on the potentiometer card 15 and will clean the insulation from the wire a slight distance back from the edge 16 of the card 15 on the upper surface, whereas the brush 61, rotating in the direction of the arrows (Figs. 4 and 10) will sweep upwardly and clean a small section of the bottom portion of the winding of the wire 18 and will wipe across the face of the wire at the edge 16. It should be noted that in cleaning the insulation from the wires 18 wound on very thin cards 15, it may be possible to make the spacer plates 116 and 140 of the same size, but, in order to clean the insulation from wire wound on thicker cards, it may be advisable to locate the wire brushes 61 and 62 as shown in the drawings.

In addition to the switch 15 operable under control of the lever 63, the motor 90, which drives the wire brushes 61 and 62, is controlled by a pair of automatically operated switches 141 and 142, a stop switch 143, a manually operable starting switch 144, and a manually operable reversing switch 145, which control the operation of a starting relay 146 and a reversing relay 147, as will be described in connection with the operation of the apparatus.

In the operation of the apparatus, power may be supplied to the motor 90 to drive the two brushes 61 and 62 after the brushes have been suitably adjusted as to height by placing spacer plates of proper thickness beneath the support plates 115 and 139 and after adjusting the depth of engagement of the brushes with the wire 18 on the cards 15 by manipulating the locating screws 107. When the brushes 61 and 62 are rotating, the apparatus is in condition for operation and, after a potentiometer card 15 has been locked in place on the table 27 by proper manipulation of the clamping assemblies 31, the operation of the apparatus may be started by removing the gage member 60 from engagement

with the card 15 on the table 27 to permit switch 15 to close (Fig. 2).

With the control circuit in the condition shown in Fig. 2, momentary operation of starting switch 144 will connect current from a source 148 through closed switch 15 (closed upon its release by gage member 60), through normally closed stop switch 143, switch 141 in the position shown, normally closed upper contacts of reversing switch 145, normally open (now closed) lower contacts of switch 144, winding of relay 146 and back to source 148, thus to energize relay 146. Upon being momentarily energized, relay 146 will lock up over its locking contacts over a circuit from the source through the winding, through contacts 149, upper contacts of switch 145, switches 141 and 143 in the position shown and switch 15 in the opposite position to that shown. When relay 146 is energized, it will supply current to the motor 88 from the source through its contacts and to drive the motor in a direction to move the carriage 83 to the left, as shown in Fig. 1. The carriage 83 will continue to move to the left (Fig. 1) until a cam 150, suitably mounted on the carriage, operates the switch 141 to move it from the position shown in Fig. 2 to engagement with its lower contact. When switch 141 is reversed, it will break the circuit to the locking contacts 149 and momentarily supply current from the source 148 through switch 15, now closed, through stop switch 143, lower contact of switch 141, upper contacts of switch 144 in the position shown, switch 142, to the winding of relay 147 and back to the source 148. In this manner, relay 147 will be energized to reverse the connections from the source 148 to the motor 88, thus to cause the motor to run in the opposite direction. Momentary energization of relay 147 will complete a locking circuit for the relay from source 148 through switch 15, now closed, stop switch 143, locking contacts 151, upper contacts of switch 144, switch 142, through the winding of the relay and back to the source 148. Power will continue to be supplied to the motor 88 through the contacts of relay 147 until the carriage 83 reaches the end of its travel to the right (Fig. 1), the left (Fig. 3), where cam 150 will operate switch 142 and stop the operation of the motor 88 after the carriage 83 has returned to its normal position. In the event that it is desired to stop the operation of the apparatus at any time, stop switch 143 may be operated to break any existing circuit to either the relays 146 or 147 and if it is desired to reverse the direction of travel of the carriage 83, switch 145 may be operated momentarily to open its upper contact and close its lower contact, thereby to supply power for momentarily energizing the relay 141, which will then lock up over a circuit from source 148 through switch 15, switch 143, locking contacts 151, upper contacts of switch 144 and switch 142 and winding of relay 147 back to the source 148. Thus, in the operation of the apparatus, momentary operation of the starting switch 144, if switch 15 has been closed by moving the gage member 60 out of the path of the brushes 61 and 62, will initiate a cycle of operation which will cause the carriage 83 to move the full length of the card 15 and back to its starting position to remove the insulation from the wire wound on the card at the edge 16.

What is claimed is:

1. An edge cleaning apparatus comprising means for supporting an article with an edge thereof in a predetermined position, a gage mem-

ber mounted on said supporting means and movable to and from operative and inoperative positions and operable in said operative positions for receiving an edge of an article thereagainst to locate said edge in said position, edge cleaning brushes, a carriage for carrying said brushes along said edge, means for driving said carriage, means including a switch member for supplying power to said driving means, said switch member being actuatable by said gage in its operative position to render said means for supplying power inoperative, and individually operable means on said carriage for individually adjusting the brushes toward and away from said edge.

2. In an edge cleaning apparatus, a stationary table for receiving an article, the edge of which is to be cleaned, a gage, means mounting said gage for movement with respect to said table, means limiting the movement of said gage in one direction to an operative position to cooperate with said table for aligning the edge of the article in a predetermined position, means for clamping said article in aligned position on said table, means limiting the movement of said gage in the opposite direction to an inoperative position to expose the edge of said article on said table, a carriage, means guiding said carriage for movement parallel to the edge of an article in said predetermined position, reversible drive means for said carriage, means to move said carriage in one direction for initiating operation of said drive means, means operable by said carriage for reversing the operation of the drive means to move said carriage in reverse direction, means mounted on said carriage for brushing the edge of the article, and means responsive to said gage means in its operative position for rendering the drive means inoperative.

3. In an edge cleaning apparatus, a table having a straight edge, means for holding an article on said table with its edge portion arranged in overlying and parallel relation to the straight edge of said table, track means extending parallel to said edge of the table, a carriage movable along said track means, means for driving said carriage, a pair of brush supporting plates on said carriage, a rotary brush mounted on each of said plates to rotate about substantially aligned axes parallel to said track means, drive means on said carriage including a motor for rotating said brushes in opposite directions, means individual to each of said plates for adjusting the position of the plates transversely of the carriage, and means for adjustably positioning each brush in spaced relation to its associated plate.

4. An edge cleaning apparatus comprising a carriage, means guiding said carriage for movement along a predetermined path, a pair of rotary brushes, means individual to each brush mounted on said carriage for supporting said brushes for rotation about axes in substantial alignment and parallel to the path of travel of said carriage, drive means on said carriage including a motor for rotating said brushes in opposite directions, means for supporting an article with its edge parallel to the path of travel of said carriage and in position to be engaged by said rotary brushes, and means on said carriage for adjusting the brushes transversely with respect to the path of travel of the carriage and to the edge of the article.

5. An edge cleaning apparatus comprising a carriage, drive means for moving said carriage

along a predetermined path, a pair of rotary brushes, means individual to each brush mounted on said carriage for supporting said brushes for rotation about axes in substantial alignment and parallel to the path of travel of said carriage, drive means on said carriage including a motor for driving said rotary brushes in opposite directions, means for supporting an article with its edge parallel to the path of travel of said carriage and in position to be engaged by said rotary brushes, means for individually adjusting said rotary brushes transversely on said carriage toward and away from the edge of said article, and means for individually adjusting said brushes vertically on said carriage to regulate the relative height thereof.

6. An edge cleaning apparatus comprising a carriage, drive means for moving said carriage along a predetermined path, a table spaced laterally from said carriage and parallel to the path of movement thereof for supporting an article with an edge to be cleaned, a gage movable transversely of the table to and from an operative position adjacent said table and an inoperative position removed from said table and operable in said operative position to align said article with the edge thereof parallel to the path of movement of said carriage, means for clamping said article against said table, and means on said carriage for engaging and cleaning the edge of said article on said table in response to the movement of said carriage.

7. An edge cleaning apparatus comprising a carriage, a rotary brush mounted on said carriage for rotation about its axis, means for rotating said brush, means guiding said carriage for movement in a path parallel to the axis of said brush, a table spaced laterally from said carriage and parallel to the path of movement thereof and having a surface in a plane parallel to the axis of said brush for supporting an article to be cleaned, a gage mounted for movement to and from an operative position on said table and operable in said operative position to align the edge of an article moved thereagainst in parallel relation to the axis of said brush and in position to be engaged by said brush, means for clamping said article in aligned position on said table, drive means including a motor for moving said carriage, and means including a switch for supplying power to said driving means, said switch being actuated by said gage in its operative position to render inoperative said means for supplying power.

8. An edge cleaning apparatus comprising a carriage, means guiding said carriage for movement along a predetermined path, a pair of rotary brushes, means individual to each brush mounted on said carriage for supporting said brushes for rotation about axes in substantial alignment and parallel to the path of movement of said carriage, drive means on said carriage for rotating said brushes in opposite directions, a table spaced laterally from said carriage and parallel to the path of movement thereof and having a surface in a plane parallel to the axes of said brushes for supporting an article to be cleaned, a gage, means mounting said gage for movement transversely of said table to and from an operative position adjacent said table and an inoperative position removed from said table, said gage in its operative position serving to align the edge of an article positioned thereagainst parallel to the axes of said brushes, clamps for clamping said article on said table, means for

adjusting said rotary brushes on said carriage transversely to the path of movement thereof toward and away from the edge of an article on said table, and means for individually adjusting said brushes vertically on said carriage to regulate the relative height thereof.

9. An edge cleaning apparatus comprising a carriage, a reversible drive means including a motor for moving said carriage along a predetermined path, means operable to start the drive means to move said carriage in one direction, means controlled by said carriage to reverse said drive means to move said carriage in the reverse direction, a rotary brush mounted for rotation on said carriage about an axis parallel to the path of movement of said carriage, driving means on said carriage for rotating said brush, a table spaced laterally from said carriage and parallel to the path of movement thereof and having a surface in a plane parallel to the axis of rotation of said brush for supporting an article to be cleaned, a gage, means mounting said gage for movement transversely of said table to and from an operative position adjacent said table and an inoperative position spaced from said table, said gage in its operative position serving to align the edge of an article positioned thereagainst parallel to the axis of rotation of said brush and in position to be engaged by said brush, means for clamping said article on said table, and means on said carriage for adjusting said brush transversely of said carriage and toward and away from the edge of an article on said table.

10. In an apparatus for cleaning a longitudinal edge of an elongated relatively flexible substantially flat article, the combination of a table having a flat surface for supporting said article thereon, a gage having a gaging surface engageable with the longitudinal edge of an article to be cleaned, means pivotally supporting said gage for movement in a predetermined path relative to said table, means limiting the movement of said gage in one direction to stop said gage in an operative position adjacent said table and with the gaging surface positioned transversely of said supporting surface for aligning in a predetermined position the edge of an article moved thereagainst, a plurality of clamps arranged to engage said article at spaced intervals and clamp said article in aligned position against said table, means limiting the movement of said gage in the opposite direction to stop the gage in an inoperative position spaced from said table to expose the edge of said article, and means for holding said gage in either its operative or inoperative position.

11. An apparatus for cleaning a longitudinal edge of an elongated relatively flexible substantially flat article comprising a carriage, a rotary brush mounted on said carriage for rotation about its axis, drive means for rotating said brush, means guiding said carriage for movement in a path parallel to the axis of said brush, a table for supporting an article thereon, said table having a flat surface in a plane parallel to the axis of said brush and a straight edge substantially parallel to the axis of said brush, a gage having a gaging surface engageable with the longitudinal edge of an article to be cleaned, means pivotally supporting said gage for movement in a direction transverse to said table,

means limiting the movement of said gage in one direction to stop said gage in an operative position adjacent said table and with the gaging surface positioned transversely of said supporting surface for aligning the edge of an article moved thereagainst in parallel relationship with the axis of said brush and in position to be engaged by said brush, a plurality of clamps arranged to engage said article at spaced intervals to clamp said article in aligned position against said table, means limiting the movement of said gage in the opposite direction to stop the gage in an inoperative position spaced from said table to expose the edge of said article, and means for holding said gage in either its operative or inoperative position.

12. An apparatus for cleaning a longitudinal edge of an elongated relatively flexible substantially flat article comprising a carriage, a rotary brush mounted on said carriage for rotation about its axis, means for rotating said brush, means guiding said carriage for movement in a path parallel to the axis of said brush, a table for supporting an article thereon, said table having a flat surface in a plane parallel to the axis of said brush and having a straight edge substantially parallel to the axis of said brush, a gage having a gaging surface engageable with the longitudinal edge of an article to be cleaned, means mounting said gage for movement in a direction transverse to said table, means limiting the movement of said gage in one direction to stop said gage in an operative position adjacent said table with the gage surface positioned transversely of said supporting surface for aligning the edge of an article moved thereagainst in parallel relationship with the axis of said brush and in position to be engaged by said brush, means to clamp said article in aligned position against said table, means limiting the movement of said gage in the opposite direction to stop the gage in an inoperative position to expose the edge of said article, means for holding said gage in either its operative or inoperative position, motor driven means for moving said carriage, and means including a switch for supplying power to said motor driven means, said switch being actuatable by said gage in its operative position to render inoperative said means for supplying power.
